FIG. 3

FIG.5

FIG.4

FIG.6

FIG. 1 is a front elevational view of a hair color processing apparatus showing my new design;

FIG. 2 is a right side elevational view thereof;

FIG. 3 is a top plan view thereof;

FIG. 4 is a rear elevational view thereof;

FIG. 5 is a right front perspective view thereof;

FIG. 6 is a bottom plan view thereof;

FIG. 7 is a left side elevational view thereof;

FIG. 8 is an enlarged transverse view of the hood along line 8—8 of FIG. 2 thereof; and

FIG. 9 is an enlarged right side elevational view of the hood thereof.

The central band portion of the hood of the apparatus is lined in FIGS. 1 to 7 and 9 to represent a darker color than the color of the upper and lower portions of the hood, and the small bands between the central band and the upper and lower portions of the hood are checkered as clearly shown in the enlarged view of the hood in FIG. 9.

I claim:

The ornamental design for a hair color processing apparatus, substantially as shown and described.
